GAME BOARD

Jules Wagner, Levittown, N. Y.

Application November 5, 1954, Serial No. 32,978

Term of patent 7 years

(Cl. D34—5)

Fig. 1

To all whom it may concern:

Be it known that I, Jules Wagner, a citizen of the United States, residing at Levittown, Nassau County, State of New York, have invented a new, original, and ornamental Design for a Game Board, of which the following is a specification, reference being had to the accompanying drawing, forming a part hereof.

Fig. 1 is a top plan view of a game board, showing my new design;

Fig. 2 is an end view thereof; and

Fig. 3 is a view of the lower left side, the other side portions being the same.

I claim:

The ornamental design for a game board, as shown.
